UNITED STATES PATENT OFFICE.

ANTONI SKUTNIK, OF DICKSON CITY, PENNSYLVANIA.

PADLOCK.

1,384,277.

Specification of Letters Patent. Patented July 12, 1921.

Application filed October 14, 1920. Serial No. 416,995.

To all whom it may concern:

Be it known that I, ANTONI SKUTNIK, citizen of the United States, residing at Dickson City, in the county of Lackawanna and State of Pennsylvania, have invented 5 certain new and useful Improvements in Padlocks, of which the following is a specification.

This invention relates to padlocks and it 10 has for an object to provide an improved and efficient padlock of simple and inexpensive construction.

A further object is to provide a padlock 15 of compact construction and neat appearance.

For further comprehension of the invention, and of the objects and advantages thereof, reference will be had to the following description and accompanying drawings, 20 and to the appended claims in which the various novel features of the invention are more particularly set forth.

Figure 1 of the drawings is a side view, with part of the casing broken away, of my 25 improved lock.

Fig. 2 is a horizontal section on the line 2—2 of Fig. 1.

Fig. 3 is a transverse section on the line 3—3 of Fig. 2.

30 Fig. 4 is a transverse section on the line 4—4 of Fig. 2.

Fig. 5 is a fragmentary perspective view showing the key in the operative relation to its coöperating parts in which the shackle is 35 released.

As here embodied my improved lock comprises a cylindrical casing 10 provided at one end with a head 11 having a suitable aperture for the key 13, the opposite end of 40 the casing being closed by a cap 14.

The shackle of my improved padlock is shown at 15 and is pivotally connected at one end as at 16 to a pair of ears 17 formed on the head 11, the shackle, comprising a 45 straight portion 15 which, when the shackle is in locked position, extends along adjacent and parallel to the casing 10, being then bowed outwardly as at 15' to form the portion which received the staple or other part, 50 and terminating in a straight end portion 15'' which extends transversely into the lock casing.

This end portion 13'' is recessed at opposite sides as at 18, a pair of hinged tumblers 55 19 being adapted to be engaged in these recesses, these tumblers extending longitudi-

nally in the casing from a common hinge or pivot 20 located adjacent the cap 14, and being adapted to swing toward or away from one another, being normally pressed toward 60 one another by means of flat springs 21 fixed in one end in the cap 14.

The key 13 may comprise a circular shank provided at one end with the usual handle element 13', the opposite, or working end of 65 the key being provided with the oppositely disposed and radially slotted projections 13'' which are adapted to engage the beveled surfaces 22 on the tumblers to move the latter away from the recesses 18 in the shackle 70 end 15''.

These beveled surfaces are located to the rear of the shackle end 15'' and the latter is formed with a slot 23 of the exact shape to receive the key with its projections. At the 75 rear of the shackle end 15'', between the tumblers 19 and in juxtaposition to the beveled faces of the latter, are a pair of transversely extending posts or pins 25 which are fixed in the casing 10 and spaced apart just sufficiently to receive the key end between them and are of a thickness corresponding to the slots or recesses in the projections. A pair of notches 26 may be formed on opposite sides of the key and adapted to prevent outward movement of the shackle end until the key is turned to releasing position.

The manner of operation of my improved lock will be readily understood from the above description, it being apparent that the 90 slots in the projections must be in registry with the posts before the key can be turned, the posts acting as guards or wards for the tumblers. In Fig. 1 the parts are shown in their locking position, and in Fig. 2 the 95 tumblers are shown moved out of engagement with the bow with the latter still in place. It will be apparent that if an attempt were made to pick the lock by means of a skeleton key the shank of the key would still hold the shackle even if the tumblers could be moved to releasing position.

Having thus described my invention what I claim as new and desire to protect by Letters Patent of the United States is as follows:

1. A padlock comprising a casing, a shackle, a pair of tumblers hinged at one end to move toward and away from one another into and out of locking engagement 110 with said shackle and having key actuatable surfaces, and a pair of transverse posts be-

tween and in juxtaposition to the said surface of the respective tumblers and forming wards therefor.

2. A padlock comprising a casing having a head at one end adapted for the insertion of a key, a shackle projecting into said casing a short distance from the opposite end, a pair of tumbler arms hinged at the last end of the casing and extending forwardly on opposite sides of the said shackle and adapted to have locking engagement with the latter, the said tumbler arms presenting key actuatable surfaces to the rear of the said shackle, said shackle being slotted at its end to permit of passage of a key therethrough.
3. A padlock comprising a casing having a head at one end adapted for the inser-

tion of a key, a shackle projecting into said casing a short distance from the opposite end, a pair of tumbler arms hinged at the last end of the casing and extending forwardly on opposite sides of the said shackle and adapted to have locking engagement with the latter, the said tumbler arms presenting key actuatable surfaces to the rear of the said shackle, said shackle being slotted at its end to permit of passage of a key therethrough, said shackle and said key being formed to permit of said shackle moving away from said key only when the latter has been turned to unlocking position.

In testimony whereof I have affixed my signature.

ANTONI SKUTNIK.
